UNITED STATES PATENT OFFICE.

CHARLES A. FORD, OF NEWARK, NEW JERSEY.

DESIGN FOR A FORK AND SPOON.

45,189.

Specification for Design.

Patented Feb. 3, 1914.

Application filed November 15, 1913. Serial No. 801,265. Term of patent 7 years.

To all whom it may concern:

Be it known that I, CHARLES A. FORD, a citizen of the United States, residing at Newark, in the county of Essex and State of New Jersey, have invented a new, original, and ornamental Design for a Fork and Spoon, of which the following is a specification, reference being had to the accompanying drawing, forming part thereof.

The figure is a plan view of a fork and spoon, showing my new design.

I claim:—

The ornamental design for a fork and spoon, as shown.

CHARLES A. FORD.

Witnesses:

HENRY BOSSET,
CORA A. BONTA.
